UNITED STATES PATENT OFFICE.

ERNST C. SCHREINER, OF TOLEDO, OHIO.

COLLAPSIBLE BARREL.

1,226,018.

Specification of Letters Patent.

Patented May 15, 1917.

Application filed January 6, 1916. Serial No. 70,659.

To all whom it may concern:

Be it known that I, ERNST C. SCHREINER, a citizen of the United States, and a resident of Toledo, in the county of Lucas and 5 State of Ohio, have invented a certain new and useful Collapsible Barrel; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to collapsible receptacles, and it particularly relates to collapsible barrels. The constructions containing my invention are particularly of value for containing articles or material which are 20 to be transported and upon reaching its destination may be emptied and may then be collapsed or folded into a relative small package or volume to be returned to the shipper.

25 The invention may be contained in many forms of packing cases and constructions usable for different purposes, all of which come within the purview of my claims hereinafter appended. To show the practi- 30 cability of my invention I have selected one of such constructions as an example and shall describe it hereinafter. The construction selected is illustrated in the accompany- ing drawings.

35 Referring to the drawings, Figure 1 is a perspective view of a collapsible barrel which I have selected for illustrative purposes. Fig. 2 illustrates a sectional view of the top or bottom cover of the barrel. 40 Fig. 3 illustrates a detail also illustrated in section in Fig. 2. Fig. 4 illustrates either end view of the collapsible barrel when the same has been folded. Fig. 5 illustrates a reinforcing band which is located, one at 45 the top and the other at the bottom of the barrel. Fig. 6 illustrates the manner in which either end cover of the barrel is locked to the reinforcing band and to the barrel body.

50 1, Fig. 1, is the barrel body, which is formed of staves. The staves are bellied and provided with beveled side edges in the manner well known in the art of barrel making. All but four of the barrel staves are 55 connected together by the chains 3 which surround the barrel body. Two of the re-

maining staves 4 are disposed on the side of the barrel opposite the remaining two, and are bound with the staves 2 when the barrel is open, as shown in Fig. 1. The chains 3 60 are formed of links 5 which have a length substantially the width of the staves. They are rectangular in form, the central portion of each link is transverse the main portion of the link and forms a pivot pin for the ad- 65 joining link. The ends of the links are located in proximity to the edges of the staves so that the staves are thus hinged together by means of the links of the chains. The links are secured to the staves 2 in any suit- 70 able way, such as by the staples 6.

The staves 4 of each pair are hinged together by means of the hinge 10 located centrally with respect to the length of the staves. They are also secured to the staves 75 2 by means of pairs of chains 11 which are located within the barrel. The ends of the chains 11 are secured to the staves 4 centrally with respect to the width of the staves, and near their ends, and to the adjoining 80 staves 2, also centrally with respect to the width of the staves 2, as illustrated in Fig. 4. When the staves 4 are in open position, that is, in barrel form, they are held in position not only by the hinges 10 but also by 85 the chains 3.

The ends of the staves are grooved in the usual manner, forming a continuous groove 38 around the edges of the barrel.

The barrels may be provided with suit- 90 able fitting covers which fit into the groove 38. The ends of the barrel may also be bound by hoops or bands 20 which will hold the ends of the staves in position. The staves will thus be tightly secured between 95 the fitting cover and the bands 20.

The barrels may also be provided with collapsible covers. In the form of the invention shown, the covers are made collapsible and readily removable, and coöperate 100 to clamp the staves of the barrel. The covers 21 are formed of two central parts 25 and two outer parts 26. The parts of each cover are hinged together as illustrated in Fig. 2. The inner parts are hinged to the outer parts by hinges 27 located on the outside of the barrel, while the two inner parts are hinged together by hinges 28 located within the barrel. An arm 29 is pivotally connected with one of the parts 26. It is 105 also connected to one of the parts 25 by means of a staple 30, in which the arm 29

has some play, to allow for the non-axial alinement of the pivot pin 31 and the pintles of the hinges 27. When the arm 29 is lifted it lifts with it parts 25 and thus reduces the width of the cover measured in the direction of the arm 29, whereupon the cover 21 may be easily removed.

In order to prevent the parts 25 and 26 which are not connected to the arm 29 from being pushed down into the barrel when the cover is inserted in the barrel, there is provided a strip 35 which is secured to the parts 26. To the one part 26 it is securely fastened to prevent relative movement between the part 26 and the strip 35, while to the other part 26 it is so secured that there may be relative longitudinal movements between the part 26 and the strip 35. It may be secured to one part 26 by means of the bolt 36 which extends through the slot 37, formed in the strip 35, thus permitting the requisite longitudinal movements of the part 26 relative to the strip 35. When the arm 29 is pushed down the part 26 will slide along the strip 35 and in the same plane that the other part 26 is located. It will thus enter in the groove 38 formed in the ends of the staves of the barrel without bellying into the barrel. The arm 29 coacting with the parts of the cover 21 and the bands 20 will thus tightly bind the staves together. When the arm 29 is forced down it may be suitably locked as by means of the hook 40, which is pivotally secured to the cover and may be turned over the pin 41 so as to engage the pin and hold the arm 29 down, and consequently the cover, in binding position. Upon opening the barrel the hook 40 may be turned back and the arm 29 lifted, which will pull the parts 25 out of the plane of the cover, and draw the parts 26 toward each other, whereupon the cover may be lifted from the barrel.

Each band 20 may also be provided with inwardly extending lips or leaves 45. They extend over the edges of the barrel and down into the interior of the barrel, and below the groove 38. The leaves 45 are also provided with grooves 46 which fit into the grooves 38 located at the ends of the barrel. The leaves 45 are also provided with flanges 47 which extend inward and at right angles to the downwardly extending portions of the leaves 45. The flanges 47 form stops against which the covers 21 may be placed in closing the barrel. The leaves 45 may also be provided with holes 48 and the parts 26 may be provided with pins 49 which, when the covers 21 are closed will enter the holes 48 and penetrate the staves located on opposite sides of the barrel. The pins and the grooves in the barrel and leaves will thus coöperate with the cover and bands to lock the parts of the barrel together.

65 When the barrel is collapsed the covers 21

may be inserted in the bands 20, and the staves 4 may be pushed inward to permit the remaining staves to be collapsed within the area defined by the chains 3. The bands 20 and the covers 21 may thus be inserted within the collapsed barrel as shown in Fig. 4.

Chains 50 may be located within the barrel to keep the covers and bands within the collapsed barrel. They extend across the ends of the barrel, one end of each chain being secured to a stave by means of a staple 51, and the other end by means of a hook 52 located on the opposite side of the barrel. After the covers 21 and the hoops 20 are placed within the collapsed barrel the chains 50 may be secured across the ends of the barrel by hooking one end of each chain on to the hook 52. This will keep the covers and hoops within the barrels for reshipping the collapsed barrel.

The construction selected and described may be greatly modified in the arrangement and manufacture of its parts and in the substitution of elements having equivalent functions, and such modifications may be used for many varied purposes and still contain the invention.

Having thus described my invention, what I claim as new, and desire to secure by Letters Patent, is,

1. A collapsible barrel having staves hinged together at their outer ends for outward hinged movements relative to each other, and pairs of staves having hinges connecting together the staves of each pair for inward hinged movements relative to each other and relative to the first named staves.

2. In a collapsible barrel, a plurality of staves hinged together at points along their edges for outward movement of adjoining staves, two pairs of staves located in diametrically opposite positions relative to the barrel, each pair of staves hinged together, and flexible members for connecting the staves of each pair to the first named staves adjoining the said pairs of staves.

3. In a collapsible barrel, a plurality of staves, two pairs of staves located in diametrically opposite positions relative to the barrel, a pair of chains, the links of the chains having lengths substantially the same as the width of the staves and secured only to the first named staves, the pairs of diametrically positioned staves being hinged together, and flexible means for connecting the staves of the pairs to the adjoining staves of the barrel.

4. In a collapsible barrel, a plurality of staves, two pairs of staves located in diametrically opposite positions relative to the barrel, a pair of chains, the links of the chains having lengths substantially the same as the width of the staves and secured

- only to the first mentioned staves, the pairs of diametrically positioned staves being hinged together, a flexible means for connecting the staves of the pairs to the adjoining staves of the barrel, and metal bands surrounding the outside of the ends of the barrel.
5. In a collapsible barrel, a plurality of staves, two pairs of staves located in diametrically opposite positions relative to the barrel, a pair of chains, the links of the chains having lengths substantially the same as the width of the staves and secured only to the first mentioned staves, the pairs of diametrically positioned staves being hinged together, a flexible means for connecting the staves of the pairs to the adjoining staves of the barrel, metal bands surrounding the outside of the ends of the barrel and having inwardly extending lips
- 10
- 15
- 20

for engaging the top of the barrel, and means for locking the band relative to the staves.

6. In a collapsible barrel, a plurality of staves, two pairs of staves located in diametrically opposite positions relative to the barrel, a pair of chains, the links of the chains having lengths substantially the same as the width of the staves and secured to the first named staves, the pairs of diametrically positioned staves being hinged together, flexible means for connecting the staves of the pairs to the adjoining staves of the barrel, metal bands surrounding the outside of the ends of the barrel, and means for securing said bands within the barrel when the same is collapsed.

In testimony whereof, I have hereunto signed my name to this specification.

ERNST C. SCHREINER.
